SCREW-OPERATED VISE HAVING WEDGE CLUTCH

Carl Stig Lennart Werne, Gothenburg, Sweden

Application January 13, 1950, Serial No. 138,738
In Sweden January 27, 1949

2 Claims. (Cl. 81—17)

1

The present invention relates to screw vises of the type which are provided with a fixed jaw, and a movable jaw slidable in guides to and from the fixed jaw.

The object of the invention is to provide a vise of the kind referred to which is simple in construction, easy to handle and efficient in its action.

The invention is broadly characterized in that between a slide slidable in guides and movable with the movable jaw, and a surface parallel to the guides of the movable jaw, there is inserted a wedge-shaped clutch member the narrower end of which is directed towards the fixed jaw, and that means are provided for forcing the movable jaw and said slide towards or from each other.

In this vise the slidable jaw can be freely slid to contact a piece of work placed between the jaws, and by forcing the slidable jaw and the slide in a direction away from each other the clutch member prevents the slide from moving backwards, so that the piece of work will be clamped.

An embodiment of the invention is by way of example shown in the accompanying drawing, wherein:

Figure 1 is a sectional view of a vise constructed in accordance with the invention;

Figure 2 is a plan view thereof; and

Figure 3 is an end view showing the vise from the rear.

In the drawing 1 denotes a base plate provided with holes 2 for screw bolts (not shown) for fastening the plate to a bench, upon which the vise is to be mounted. To the upper face of the base plate there are secured, such as by welding, two parallel guide bars 3 and 4 of U-shaped cross-section which are spaced apart. To one end of said guide bars there is secured a cross piece 7 forming the fixed jaw of the vise. The other jaw 8 of the vise is secured to one end of a left-hand threaded screw sleeve 9, which by means of an intermediate piece 10 is secured to a slide 11 slidable in and along the channels of the guide bars 3 and 4. On the side of the slide 11 remote from the cross piece 7 another slide is slidable in and along the guide bars 3, 4, said other slide comprising a right-hand threaded screw sleeve 12 coaxial with the sleeve 9, an intermediate piece 13 projecting down between the upper flanges 6 of the respective guide bars 3, 4 and a slide block 14, which is embraced by said flanges and the bottom side of which is provided with an inclined surface 15. Between

5 said surface and the channel surfaces 16 formed by the lower flanges 5 of the guide bars 3, 4, there is inserted a wedge-shaped clutch member 17 having its narrower end directed towards the slide 11, and provided at its surface contacting said channel surfaces 16 with a series of transverse grooves 18. The clutch member 17 is actuated by a plate spring 20 secured to the slide block 14 by means of screws 19, and adapted to 10 keep the clutch member 17 pressed with a suitable force between the surface 15 of the slide block 14 and the channel surfaces 16. In the space 21 between the screw sleeves 9 and 12 there is disposed the middle portion of a screw spindle 23 having a suitable handle 22. The end portions 24, 25 of said screw are inserted respectively in the sleeves 9, 12, one of said end portions being right hand threaded, while the other is left hand threaded, so that by rotating the screw 23 by means of the handle 22 in one direction or the other the screw sleeves 9, 12 and the elements connected to them can be forced towards or from each other.

20 The vise described acts in the following manner.

When a piece of work is to be clamped, the screw sleeves 9, 12 and the elements connected to said sleeves are slid en bloc towards the fixed jaw 7, the clutch member 17 permitting said 25 sliding movement because, even under the influence of the spring 20, only a slight frictional resistance is exerted thereby. The piece of work, in this way, is preliminarily gripped between the jaws 7, 8 whereupon by partially rotating the handle 22 and thus the screw 23 in a clockwise direction (according to Figure 3), the screw sleeves 9, 12 are forced in the direction away from each other. As the clutch member 17 prevents a backward movement of the screw-sleeve 12, the jaw 8 is effectively forced in a direction towards the jaw 7, so that the piece of work is firmly gripped. When the piece of work is to be released it is sufficient simply to turn the spindle in the opposite direction. If the screw sleeves are to be moved away from the fixed jaw 7, the handle 22 and with it the screw 23 is turned so far in an anticlock-wise direction (according to Figure 3) that the slide 11 abuts against the narrower end of the clutch member 17 and slides said member against the action of the spring 20, whereby the friction grip between the clutch member and the slide-surfaces 16 ceases, and the desired backward movement of the screw sleeves can be freely performed.

55 The present vise is capable of considerable

modification and such changes thereto as come within the scope of the appended claims is deemed to be a part of the invention.

What I claim is:

1. A screw vise comprising a base, a jaw fixedly mounted on said base, means forming guideways extending towards said fixed jaw and mounted on said base, a jaw carrying slide slidably mounted on said guideways, a second slide slidably mounted on said guideways and having the side thereof facing the bottom of said guideway slanting downwardly towards said first mentioned slide, a wedge providing a locking clutch for said second slide being slidably positioned between said slanting bottom of said second mentioned slide and the bottom of said guideway with the thin edge of said wedge extending from said second slide towards said first slide for being moved to an unclutching position upon contact therewith, means for moving said slides in opposite directions at the same time along said guideways, and resilient means tending to retain said wedge beneath said second slide.

2. A screw vise comprising a base, a jaw fixedly mounted on said base, means forming guideways extending towards said fixed jaw and mounted on said base, a jaw carrying slide slidably mounted on said guideways, a second slide slidably mounted on said guideways and having the side thereof facing the bottom of said guideway slanting downwardly towards said first mentioned

slide, a wedge providing a retaining clutch for said second slide being slidably positioned between said slanting bottom of said second slide and the bottom of said guideway with the thin edge of said wedge extending from said second slide towards said first slide and said fixed jaw whereby movement of said second slide from said fixed jaw causes said wedge to retain said second slide in position and movement of said slides towards one another causes said first slide to move said wedge to an unclutched position relative to said second slide, means for moving said slides in opposite directions along said guideways at the same time, and a resilient finger mounted on said second slide and contacting the thick edge of said wedge for tending to move said wedge with said second slide during its movement towards said fixed jaw.

CARL STIG LENNART WERNE.
